158,890

RAILWAY DINING CAR TABLE

Frank L. Murphy, Chicago, and Hollinshead T. Martin, Evanston, Ill., assignors to Pullman-Standard Car Manufacturing Company, Chicago, Ill., a corporation of Delaware

Application September 20, 1947, Serial No. 141,501

Term of patent 14 years

(Cl. D33—14)

To all whom it may concern:

Be it known that we, Frank L. Murphy, and Hollinshead T. Martin, citizens of the United States of America, and residents, respectively, of Chicago, county of Cook, and State of Illinois, and Evanston, county of Cook, and State of Illinois, have invented a new, original, and ornamental Design for a Railway Dining Car Table, of which the following is a specification, reference being had to the accompanying drawing, forming part thereof.

In the drawing—

Fig. 1 is a general perspective view of a railway dining car table showing our new design;

Fig. 2 is a side elevational view of the dining table;

Fig. 3 is a plan view; and

Fig. 4 is a front elevational view of the dining table.

We claim:

The ornamental design for a railway dining car table, substantially as shown.

FRANK L. MURPHY.
HOLLINSHEAD T. MARTIN.
